DESIGN FOR A SPARK PLUG

Purvis D. Jackson, Chicago, Ill.

Application October 7, 1935, Serial No. 58,877

Term of patent 14 years

To all whom it may concern:

Be it known that I, Purvis D. Jackson, a citizen of the United States, residing at Chicago, Illinois, have invented a new, original, and ornamental Design for a Spark Plug, of which the following is a specification, reference being had to the accompanying drawing, forming part thereof, in which

The figure shows a perspective view of my new design for a spark plug, with the insulator of said

plug portion having contrasting colors between adjacent surfaces on said insulator portion in the upper part thereof. Colored portions on the surface of the insulator are indicated by cross hatched lines on the drawing in contrast to the color of the adjacent surface area.

I claim:

The ornamental design for a spark plug as shown and described.
